Patented June 15, 1920.

UNITED STATES PATENT OFFICE.

JOHN PLUCIENSKI, OF SYRACUSE, NEW YORK.

SANITARY CUSPIDOR.

1,343,406.

Specification of Letters Patent. Patented June 15, 1920.

Application filed March 22, 1920. Serial No. 387,956.

To all whom it may concern:

Be it known that I, JOHN PLUCIENSKI, a citizen of the United States, residing at Syracuse, in the county of Onondaga and State of New York, have invented certain new and useful Improvements in Sanitary Cuspidors, of which the following is a specification.

This invention relates to improvements in 10 cuspidors, and has for its object to provide a novel, simple, and convenient sanitary device of the class, which is supported by a bracket, the latter being arranged for convenient attachment to a wall, or other support. 15 port, for positioning the device above and clear of the floor. A further object is to provide a substantial casing, open at its top, in which is disposed a removable sputum tray, the said casing having a hinged cover 20 for excluding flies, as well as for preventing the escape of odors from the tray. And a further object is to provide novel and simple means for mechanically lifting the cover for permitting access to the tray.

25 I attain these objects by the means set forth in the detailed description which follows, and as illustrated by the accompanying drawing, in which—

Figure 1 is a top-plan view of the complete device, in which a portion of the cover is cut away. Fig. 2 is a front side elevation of the same. Fig. 3 is a central vertical cross-section, taken on line 3—3 of Fig. 2. Fig. 4 is an end elevation of the device, 35 showing by full and dotted lines the closed and the open positions of the cover, and the means for operating the same. And Fig. 5 is a broken rear side elevation of the device.

In the drawing, 2 represents the body or 40 outer casing of the cuspidor, which has an open top 2'. The rear side of the body is provided with two integral spaced perforated hinge-lugs 2^a. 3 designates a cover for the body, the said cover having a continuous 45 depending flange 3', which telescopes the top of the body. The cover is provided with two spaced depending hinge-lugs 3^a, having perforations which aline with those of the lugs 2^a, and receive a pintle rod 3^b. The 50 lugs 2^a are preferably spaced sufficiently to receive therebetween the lugs 3^a. Within the hollow body 2 is disposed a removable tray-like sputum cup 4, which is also open 55 at its top, and is provided at its opposite ends with recesses 4', which afford finger-holds for removing the tray. The cover 3

may be lifted manually, for removing the tray 4, or for the usual salival deposit therein, like any similar cover, but I prefer to use novel and simple mechanical means 60 therefor, so as to avoid manual contact with the cover. For this purpose I provide a hand-lever 5, of peculiar shape, which is pivoted to one end of the body 2 by a pin 5'. The lever 5 has a curved portion 5^a, which 65 is normally in engagement with the lower edge of the flange 3'. When the user of the cuspidor depresses the opposite end of said lever, the end 5^a raises the cover, as from the full line, to the dotted line position, 70 shown in Fig. 4. The user has the choice of either grasping the outer end of the lever 5 and depressing the same by hand, or he may effect the operation of said lever by means of a pedal (not shown), which may connect 75 in a well-known manner with an operating rod 6 (see Fig. 4). The lever 5 is preferably so arranged that when it lifts the cover to its full extent, the latter still inclines slightly forwardly and therefore tends to 80 gravitate back to the closed position. In order to quicken, as well as to effect the positive closing of the cover 3, I provide a spring 7, which is disposed substantially 85 vertically at the rear side of the body 2, the said spring being so arranged that after the first slight opening movement of the cover, the latter engages and flexes the spring, as shown by dotted lines in Fig. 4. As soon as the operator lets go the lever 5, the spring 90 7 forces the cover forwardly and during the subsequent closing movement, the cover restores the lever 5 to the full line position, shown in Fig. 4. The spring 7 is supported by a cleat 8, which is secured to the rear 95 side of the body 2, beneath the lugs 2^a, by screws 8'. One side of the cleat 8 is cut away at 8^a, to receive the tapering upper end of a bracket 9, which extends downwardly and rearwardly, and its lower end 100 is provided with a footing 9', by which the said bracket may be suitably secured to a wall, desk, or other support.

My cuspidor is extremely simple, convenient, and sanitary. It is particularly 105 adapted for use by doctors, dentists, and in offices, to take the place of the common open cuspidors, which usually rest upon the floors, and constantly emit their disagreeable odors. By mounting my cuspidor upon the 110 bracket 9, it may be disposed in various convenient, but out-of-the-way places, without

danger of it being upset, and without obstructing or littering up the floors.

Having thus described my invention, what I claim, is—

- 5 A cuspidor, comprising a hollow body having an open top, a hollow cover hinged to the rear side of the body, said cover having a continuous depending flange overlapping said open top when the cover is closed,
- 10 a lever pivoted to one end of the body having a curved portion in frictional engage-

ment with the bottom edge of said depending flange adapted when rocked in one direction to swing said cover upwardly through an arc of less than 90°, tension 15 means for moving said cover and said lever in the opposite direction, and means for mounting said body upon a supporting bracket.

In testimony whereof I affix my signature. 20

JOHN PLUCIENSKI.
